UNITED STATES PATENT OFFICE.

JOHN THOMAS McGRATH, OF PORT HURON, MICHIGAN.

MOTOR.

SPECIFICATION forming part of Letters Patent No. 757,485, dated April 19, 1904.

Application filed July 16, 1903. Serial No. 165,858. (No model.)

To all whom it may concern:

Be it known that I, JOHN THOMAS McGRATH, of the city of Port Huron, in the county of St. Clair, in the State of Michigan, have invented 5 certain new and useful Improvements in Motors, of which the following is a specification.

My invention relates to improvements in motors; and the object of the invention is to devise a simple, efficient, and quickly-reversible motor capable of instantaneous control adaptable to the driving axle or shaft of the gear which operates the machine to be driven; and it consists, essentially, of a substantially triangular casing with a suitable orifice to admit the air under pressure, such casing being hermetically sealed, so as to retain the air under pressure, and being provided, preferably, with two cylinders having their rods connected to a crank-wheel, a sliding valve supported 20 on suitable links at the heads of the cylinders, and a slide-valve for controlling the admission and exhaust of the air from the cylinders, all being arranged as hereinafter more particularly explained.

Figure 1 is a side elevation showing the cylinders and slide-valves at the head thereof in section. Fig. 2 is an enlarged longitudinal section on the line *a b*, Fig. 1. Fig. 3 is a longitudinal section on the line *c d*, Fig. 1. Fig. 4 is a sectional plan on the line *e f*, Fig. 1.

In the drawings like characters of reference indicate corresponding parts in each figure.

A is the side of the casing, which is of polygonal form and having a suitable cover-plate 35 *A'* and inlet-orifice *A*².

B is the main shaft, and *C* the crank-wheel thereof.

D D are cylinders. Each cylinder *D* is provided with a piston *d*, which is connected by 40 a piston-rod *d'* to the wrist-pin *d''* on the crank-wheel. Each cylinder *D* is also provided with a short passage-way 2, leading to the top end of the piston, and a long passage-way 3, leading to the bottom end of the piston. The passage-ways 2 and 3 converge at the top of the cylinder, as indicated.

E is a pin, the reduced threaded inner end *e* of which fits into a corresponding socket *A*³ in the boss *A*⁴ in the casing *A*. The outer

end of the pin is provided with a nut *e'*, and 50 the pin intermediate of its length is provided with an annular recess *e*².

*e*³ is a spring encircling the pin *E* and extending between the cylinder and the cover-plate *A'*. The pin *E* forms the point upon 55 which the cylinder *D* oscillates.

F is a slide-valve which is connected by the link *f* to a pin *f'* forming part of the casing. The slide-valve is held upon the seat on the top of the cylinder by means of the air-pressure 60 within the casing, and such slide-valve is provided with the side ports 4 and 5 and central port 6.

G and *G'* are passage-ways formed in the casing *A* on the back plate. The passage-ways *G* and *G'* cross each other without communicating with each other at the point of crossing, the casting being so formed. The passage-way *G* at the left hand leads to ports 4 and 5 in the slide-valve and at the right hand 70 leads to the port 9 in the cylinder, and the passage-way *G'* at the left hand leads to the port 9 in the cylinder and at the right hand to the ports 4 and 5 in the slide-valve. In each case where the passage-way *G* or *G'* communicates with the slide-valve it passes into a passage-way 7, which communicates by a passage-way 7', as indicated by dotted lines, to the ports 4 and 5, which communicate with the ports 3 and 2, respectively, in the cylinder. In each case where the passage-way *G* or *G'* communicates with the cylinder it passes into a port 9, thence into the annular recess *e*², which communicates with the port 80 8, which in turn communicates with the port 6 in the slide-valve, which communicates alternately with the ports 2 and 3 in the cylinder.

Intermediate of the length of the passage-ways *G* and *G'*, I provide the controlling slide-valve *H*, which is provided with a cavity *h*, which is designed to straddle the passage-way *G* and exhaust-port 10 or the passage-way *G'* and exhaust-port 10. The slide-valve *H* is supported in suitable guideways *h'*. The 90 slide-valve is manipulated by means of an arm 11, fixed on a pin 12, which is operated by a suitable lever. As will hereinafter ap-

pear, the position into which the slide-valve H is thrown will regulate the direction of rotation of the shaft B.

It will of course be understood that either 5 of the passage-ways G or G' will be open to the interior of the casing, and in the drawings in Fig. 3 I show the passage-way G' open to the interior of the casing—that is to say, the machine in an upright position and designed 10 to be operated by the pressure of the air passing through the passage-way G'.

Having now described the construction of my invention, I shall proceed to point out the mode of operation of the same. As the air 15 passes through the passage-way G' to the right it necessarily passes into the cavity 7, thence into the port 4, which communicates with the port 3, and passes into the interior of the cylinder, forcing the piston d upwardly 20 and the crank-wheel in the direction indicated by arrow. At the same time the air passes through the passage-way G' to the left into the port 9, thence successively through the recess e', port 8 into the cavity 6, thence (when 25 the cylinder further oscillates) into the port 3 of the companion cylinder, thereby serving to force the piston d upwardly and pull the crank-wheel C, and consequently rotate the shaft B, in the direction indicated by arrow. 30 The exhaust, however, passes outwardly through the then exhaust passage-way G by a course exactly the reverse of that already described, thence into the cavity h in the controlling slide-valve H and exhaust passage-way 10. When the slide-valve H is placed 35 so as to cover the exhaust passage-way 10 and passage-way G', of course the direction of rotation is reversed.

It is to be understood that although I have 40 described my invention as being adapted to be driven by compressed air it might be driven by any other suitable fluid—such as gas, water, steam, or the like—though air is the preferable source of power. It is also to be understood that I do not wish to limit myself to the exact details of construction as herein 45 shown and described; but I wish to be able to vary the construction of device within the scope of ordinary mechanical skill.

50 What I claim as my invention is—

1. In an air-motor, the combination with the casing, main shaft and crank-wheel, of the oscillating cylinders provided with passage-ways leading from each end thereof to the top 55 thereof, coacting slide-valves supported on links and passage-ways leading to the slide-valves and cylinder passage-ways as and for the purpose specified.

2. In a device of the class described, the combination with an air-tight casing, of the main shaft, a crank-wheel secured thereto, a pair of oscillating cylinders located in the casing, the piston - rods operatively connected to the crank-wheel, the slide-valves coacting with

the cylinders, inlet and exhaust openings for 65 the casing, supply-passages communicating between the inside of the casing and the cylinders and slide-valves and exhaust-passages communicating between the exhaust-outlet and the cylinders and slide-valves as and for 70 the purpose specified.

3. In a device of the class described, the combination with a suitable air-tight casing, of the main shaft, the crank-wheel secured thereto, a pair of oscillating cylinders located in 75 such casing, the piston-rods operatively attached to the crank-wheel, the slide-valves coacting with the cylinders, inlet and exhaust openings for the casing, inlet-passages communicating between the inside of the casing 80 and the cylinders and slide-valves, and exhaust-passages communicating between the exhaust-outlet and the cylinders and slide-valves, and a reversing-valve as and for the purpose specified.

4. In a device of the class described, the combination with the casing, the main shaft and crank-wheel, of the oscillating cylinders and their pistons and the piston-rods connected to the crank-wheel, said cylinders having passage-ways leading from each end thereof to the top thereof, coacting slide-valves supported on links, a pair of passage-ways one communicating on its right with the passages of the right-hand cylinder and on its left with 90 the valve of the left-hand cylinder, and the other passage-way communicating on its right with the slide-valve of the right-hand cylinder and on its left with the passage-way of the left-hand cylinder and means for connecting 95 either one of said passages with the interior of the casing and the other with the exhaust-opening as and for the purpose specified.

5. In a device of the class described, the combination with the casing having the supply and 105 exhaust passage-ways, of the main shaft and crank-wheel, the oscillating cylinders and their pistons connected to the crank-wheel, the coacting slide-valves and their link connections with the casing, said slide-valves being adapted to slide on valve-seats on the tops 110 of the cylinders and said slide-valves and cylinders having sliding contact with valve-seats formed integral with the casing, shafts upon which the cylinders are pivotally mounted, 115 springs encircling said shafts and adapted to force the cylinders against the casing valve-seats, said cylinders and slide-valves having suitable ports and passages to form communication between the inlet and exhaust pas- 120 sages and the portions of the cylinders above and below the pistons alternately as and for the purpose specified.
